DESIGN FOR A BOTTLE INSPECTION MACHINE

Everett Worthington, New York, N. Y.

Application August 24, 1938, Serial No. 79,534

Term of patent 14 years

To all whom it may concern:

Be it known that I, Everett Worthington, a citizen of the United States and resident of New York, New York County, New York, have invented a new, original, and ornamental Design for a Bottle Inspection Machine, of which the following is a specification, reference being had to the accompanying drawings, forming part thereof.

Fig. 1 is a perspective view of a bottle inspection machine showing my new design as viewed from the feeding end;

Fig. 2 is likewise a view in perspective illustrating the discharge and reject side thereof;
Fig. 3 is a side view;
Fig. 4 is a back view of my machine;
Fig. 5 is a front view thereof; and
Fig. 6 is a plan view of the same.

I claim:

The ornamental design for a bottle inspection machine, as shown.

EVERETT WORTHINGTON.
